UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed May 28, 1925. Serial No. 33,353.

To all whom it may concern:

Be it known that I, GEORGE CLAUSING, a citizen of the United States, residing at Portsmouth, in the county of Scioto and 5 State of Ohio, have invented certain new and useful Improvements in Lasts, of which the following is a specification, reference being had therein to the accompanying drawing.

10 My invention relates to lasts.

It is the object of my invention to provide a last in which the toe part and heel part are pivoted on one another and are connected by a solid link having springs in 15 the ends thereof to resist movement of the last parts from one position to the other and to hold the parts in either position yieldingly.

Referring to the drawings:

20 Figure 1 is an elevation of the last parts partially in section showing the position of the link and springs in expanded position;

Figure 2 is a similar view showing the parts when the springs are flexed as the 25 parts pass over dead center or the center of movement; and

Figure 3 is a section on the line 3—3 of Figure 1.

Referring to the drawings in detail, 1 is a 30 toe part and 2 is a heel part which rock upon one another through a knuckle joint consisting of a transverse projecting circular shoulder 3 and a receiving socket 4. The forward face of the heel part above the 35 joint is cut away as at 5. Below this joint is a vertical face 6 which acts as a limiting shoulder for the parts engaging with the shoulder 7 on the toe part. Through these shoulders the expanding movement of the 40 last parts is limited. The forward last part or the toe part is provided with a slot 8 and the rear part is provided with a slot 9. In these slots or grooves is located the solid link 10. This link has expanded heads 45 11 with substantially T-shaped slots 12 arranged transversely thereof, anchor pins being located in the bottom of the slots. Such anchor pins are designated respectively 13 and 14. The ends of these slots as at 15 are 50 slightly arched to permit the springs 16 carried between the anchor pins and the ends 15 of the slots to flex when the parts pass over dead center. Thus the bottom of the T-shaped slot positions the link with respect 55 to the anchor pin. The sides of the slots

position the springs 16. The last parts rock about the center 17. The centers of the anchor pins 13 and 14 are so arranged that a line drawn between such centers is below the center of movement 17 when the parts 60 are in expanded position and above said point when they are in collapsed position; said line passes over said center of movement when the parts are moved from one position to the other. Due to the fact that 65 in passing over this dead center the distance between the anchor pins lengthens, this will cause the springs 16 to flex and the movement of the parts will be resisted or the parts will be maintained in position 70 yieldingly.

I prefer to employ two of such plates 10 side by side having coinciding slots and using the same anchor pins, and preferably 75 using the same spring 16.

It will be understood that I desire to comprehend within my invention such modifications as may be necessary to adapt it to varying conditions and uses.

Having thus fully described my invention, what I claim as new and desire to secure by Letters Patent, is:—

1. In a last, a toe part and a heel part, a link connecting said parts, and yielding means comprising vertically arranged spring plates 80 separably mounted in the ends of said link to resist the movement of the last parts from expanded or collapsed positions.

2. In a last, a toe part and a heel part, a link connecting said parts, yielding means comprising vertically arranged spring plates 85 separably mounted in the ends of said link to resist the movement of the last parts from expanded or collapsed positions, and means to support said link arranged in each of 90 said last parts, said means being so arranged that the lines drawn between the centers thereof will be to one side of the center of movement of the last parts in either expanded or collapsed position of the parts. 100

3. In a last, a toe part and a heel part adapted to rock one upon the other about a center of movement, an anchor pin in the heel part, an anchor pin in the toe part, a link mounted on said pins, said link having 105 a T-shaped slot at each end thereof with the pins in the base of the slots normally, and vertically arranged spring plates arranged in said slots between the pins and the ends of the link, said pins engaging with 110

said spring plates, said slots being sufficiently cut away to permit of the flexing of the springs when the pins engage therewith upon the movement of the parts from expanded or collapsed positions.

4. In a last, a toe part and a heel part adapted to rock one upon the other about a center of movement, an anchor pin in the heel part, an anchor pin in the toe part, a link mounted on said pins, said link having a T-shaped slot at each end thereof with the pins in the base of the slots normally, vertically arranged spring plates arranged in said slots between the pins and the ends of the link, said pins engaging with said spring plates, said slots being sufficiently cut away to permit of the flexing of the springs when the pins engage therewith upon the movement of the parts from expanded or collapsed positions, said pins being so arranged that a line drawn between their centers will be to one side of the center of movement of the parts in either expanded or collapsed position.

5. In a last, a toe part and a heel part adapted to rock one upon the other about a common center of movement, links connecting said parts, an anchor pin in each of said parts supporting said links, T-shaped slots in which said pins are located in the ends of said links, said slots and said links coinciding, and a common vertically disposed spring plate arranged in each end of said links engaging with said pins whereby said springs are flexed when the parts are moved from expanded or collapsed positions.

6. In a last, a toe part and a heel part adapted to rock one upon the other about a common center of movement, links connecting said parts, an anchor pin in each of said parts supporting said links, T-shaped slots in which said pins are located in the ends of said links, said slots and said links coinciding, and a common vertically dis-

posed spring plate arranged in each end of said links engaging with said pins whereby said springs are flexed when the parts are moved from one position to the other, said pins being arranged so that the centers thereof are to one side of the center of movement in either expanded or collapsed position.

7. In a last, a toe part and a heel part adapted to rock one upon the other about a center of movement, an anchor pin in the heel part, an anchor pin in the toe part, a link mounted on said pins, said link having a T-shaped slot at each end thereof with the pins in the base of the slots normally, and vertically arranged spring plates arranged in said slots between the pins and the ends of the link, said pins engaging with said spring plates, said slots being sufficiently cut away to permit of the flexing of the springs when the pins engage therewith upon the movement of the parts from expanded or collapsed positions, the pin in the heel part being closer to the center of movement than the pin in the toe part.

8. In a last, a toe part and a heel part adapted to rock one upon the other about a center of movement, an anchor pin in the heel part, an anchor pin in the toe part, a link mounted on said pins, said links having a T-shaped slot at each end thereof with the pins in the base of the slots normally, and vertically arranged spring plates arranged in said slots between the pins and the ends of the link, said pins engaging with said spring plates, said slots being sufficiently cut away to permit of the flexing of the springs when the pins engage therewith upon the movement of the parts from expanded or collapsed positions, said links having expanded heads to accommodate said springs, slots and pins.

In testimony whereof, I affix my signature.

GEORGE CLAUSING.
